UNITED STATES PATENT OFFICE

HARLEY A. W. HOWCOTT, OF NEW ORLEANS, LOUISIANA

COLLAPSIBLE BARREL

Application filed July 25, 1928. Serial No. 295,137.

My invention relates to improvements in collapsible containers, and especially those wherein a plurality of hingedly connected sections may be readily disconnected, permitting storage of such containers in a limited space, and it consists in the combinations, constructions, and arrangements herein described and claimed.

An object of my invention is to provide a container which may be readily assembled and dismantled without the use of special tools.

A further object of my invention is the provision of stave sections which may be hingedly connected, and each hinge formed with flange members cooperating with the next adjacent stave so as to provide a tight joint at the junction of the staves.

A still further object of my invention is the provision of end closure members cooperating with the stave sections in such manner as to brace the stave sections upon their inner sides, thus adding to the rigidity of the container.

A still further object of my invention is to provide end section of a collapsible nature which may be readily removed from a container, and also to provide locking means whereby said closures will be positively held in engagement with the stave sections.

Other objects and advantages will appear in the following specification, and the novel features of the invention will be particularly pointed out in the appended claims.

My invention is illustrated in the accompanying drawings, forming part of this application, in which:—

Figure 1 is a perspective view of a container embodying my invention.

Figure 2 is a sectional view on the line 2—2 of Figure 1.

Figure 3 is a cross section on the line 3—3 of Figure 2.

Figure 4 is a perspective view of one of the stave sections.

Figure 5 is a perspective view illustrating one of the end closures and locking means.

I construct a barrel or container made up primarily of a desired number of stave sections 1, which when connected will produce

the complete body of the barrel. It is understood that any number of sections may be employed, and that the staves may have the general contour of ordinary barrel staves, presenting a bilged effect. The staves may be formed from any suitable material, such as wood or metal, and in either event, one longitudinal edge of each stave is provided with projecting apertured hinge ears 2, adapted to cooperate with the next adjacent stave as will be explained. The opposite edge of the stave is provided with an offset flange 3, providing a recess 4, for reception of an abutting stave section. The ends of the flange 3 stop short of the stave ends and a portion of the stave is cut away to provide a shoulder 5, in which shoulder there is provided a threaded opening 6. (See Figure 4.) At opposite ends of each stave section and extending circumferentially, there are provided kerfs or channels 7, for reception of the end closure members.

In assembling a barrel or container, the desired number of stave sections are selected, these sections being arranged so that the edge lies within the recess 4 of the next adjacent stave, with the apertures of the ears 2 in alignment with the aperture 6 of the abutting stave. A bolt 8 is then secured to the ear 2 into threaded engagement with the aperture 6. It will thus be seen that the sections 1 are hingedly connected to one another, and that the juncture of the sections 1 are effectively closed by the offset flange 3 overlying the adjacent stave.

The heads of the barrel are composed of three sections 9, 10 and 11, so shaped and of a size to be accommodated within the kerf 7 of the barrel staves when assembled to form the barrel body. It will be noted, by reference to Figures 1 and 2, that the sections 9 and 11 are rigidly held within the kerf 7 and that the section 10 is removably arranged between the sections 9 and 11. The section 10 is composed of two sections 10^a and 10^b, each of which is provided with handles 12, hinged to the sections 10^a and 10^b as at 13. The handles 12 are secured upon the sections 10^a and 10^b adjacent their abutting edges, and are of a length to extend across and overlap

the opposite section 10^a or 10^b, as the case may be. The handles 12 may be of any desired shape, but in the present instance, I have shown them as substantially rectangular, having hand holds 14 and being apertured as at 15. (See Figure 5.)

Assuming that a barrel body has been assembled, and it is desired to close the ends, the sections 9 and 11 are inserted into the open ends of the barrel, and adjusted within the kerf 7 on opposite sides of the barrel, leaving the central portion of the barrel open. The sections 10^a and 10^b are next introduced between the sections 9 and 11. This is readily accomplished by arranging the sections 10^a and 10^b, as shown in Figure 5. A downward pressure on these two sections will cause engagement of these sections, at the outermost parts with the kerf 7. The entire cover may now be securely held in this position by swinging of the handles 12 downwardly to lie in a plane parallel with the cover, and securing the handles by insertion of a threaded fastening member 16 through the apertures 15 into respective sections 9 and 11.

To gain access to the interior of the barrel, it is only necessary to remove the fastenings 16, grasp the handles 12, exerting an upward pull, this movement of the parts causing disengagement with the kerf 7.

In order to provide an even surface to the exterior of the container, the flanges may be connected by circumferential ribs 17. The provision of such ribs will permit ready rolling of a barrel, if it is so desired.

From the foregoing description, it will be readily seen that I have provided a container which may be readily collapsed; that the joints abutting each stave section are effectively sealed when assembled; and that said container when constructed as here shown and described will be strong and durable, easily assembled and cheap to manufacture.

I claim:

1. A barrel having its body portion made up of a plurality of stave sections, each stave section having one of its longitudinal edges formed with an offset flange, the opposite longitudinal edge being provided with ear members, said flange and first named longitudinal edge being provided with shoulders for engagement by said ear members, and means connecting said stave sections.

2. A barrel having its body portion made up of a plurality of stave sections, each stave section having one of its longitudinal edges formed with an offset flange providing a recess, said flange and longitudinal edge terminating inwardly of the outer edges and providing shoulders, said shoulders being provided with threaded apertures, the opposite longitudinal edge of each stave being provided with apertured ear portions, said portions being of size to engage snugly upon said shoulders, whereby to cause contacting

of abutting longitudinal edges of respective stave sections within said recess and connecting means engageable through said apertured ears and shoulders.
